UNITED STATES PATENT OFFICE.

FRANK C. BRASTOW, OF LISBON, NEW HAMPSHIRE.

GARBAGE-CAN CONTAINER.

Application filed December 22, 1925. Serial No. 77,021.

This invention relates to improvements in receptacles and is more particularly adapted to a container which is placed in a well or opening formed in the ground for receiving and containing a garbage can, a cover being provided for the receptacle whereby access to the garbage can by animals or rodents will be prevented.

A further object of the invention is to provide a garbage can container of the above mentioned character which includes a means for supporting the garbage can within the container in such a manner as to space the bottom of the can from the bottom of the well, thus enabling the earth to absorb the odors arising from the garbage can, and further preventing the bottom of the can from freezing to the ground such as frequently occurs when a garbage can rests on the ground.

A still further object is to provide a garbage can container of the above mentioned character which is simple in construction, inexpensive, strong and durable and furthermore well adapted to the purpose for which it is designed.

Other objects and advantages of the invention will become apparent during the course of the following description taken in connection with the accompanying drawing.

In the accompanying drawing forming a part of this application and in which like numerals designate like parts throughout the same:

Figure 1 is a view partly in elevation and partly in section of the container embodying my invention showing the same in position in a well formed in the ground and showing the manner in which the garbage can is supported within the container, and

Figure 2 is a transverse section through the container showing the garbage can supporting member mounted therein in top plan.

In the drawing wherein for the purpose of illustration is shown the preferred embodiment of my invention, the numeral 1 designates generally my improved garbage can container, the same including the side walls 2 and the corner posts 3. The receptacle or container is substantially rectangular in cross section and is open at its top and bottom, a suitable cover being provided for the top, and if desired, this top may be hingedly associated with one of the side

walls to permit the easy opening or closing of the top of the container. In the present instance, the container is being shown as constructed of wood and furthermore each of the side walls is formed of a plurality of sections which construction is more clearly illustrated in Figure 1. However, I do not wish to limit myself to the particular material which may be used in constructing my improved container, nor do I wish to be limited to the particular shape, it being understood that the container is of such size as to accommodate household garbage cans of the well known construction and now universally manufactured.

A pair of transversely extending cross bars 5 and 6 respectively are arranged horizontally within the container and extend between the pairs of corner posts in the manner shown more clearly in Figure 2, the cross bars being secured to the corner posts in any suitable manner. These cross bars cooperate to support a shelf or platform 7. The shelf rests on the intermediate portions of the cross bars and the longitudinal side edges of the shelf are spaced from the adjacent side walls of the container. In this manner, the shelf will be supported within the container at a point above the bottom of the well A, which is formed in the ground and in which the container is adapted to be disposed.

As is clearly shown in Figure 1, a garbage can B of any well known type is placed within the container and the bottom of the can will rest on the shelf or platform 7, and when the cover 4 is placed over the open top of the container, there will be no possibility of animals or rodents obtaining access to the container and the garbage can supported therein. By supporting the bottom of the can in spaced relation with respect to the bottom of the well formed in the ground, the earth in the bottom of the well tends to absorb the odors arising from the garbage receptacle and also there will be no possibility of the bottom of the can becoming stuck to the ground as often results when a garbage can is resting on the surface.

A device of the above mentioned character will promote sanitation and by supporting a garbage can under ground, the container will not present an unsightly appearance.

The simplicity in which my improved container is constructed enables the same to be

readily and easily set up in position for use and may furthermore be easily disassembled for storing or transporting purposes.

While I have shown the preferred embodiment of my invention it is to be understood that minor changes in the size, shape and arrangement of parts may be resorted to without departing from the spirit of the invention and the scope of the appended claim.

Having thus described the invention, what I claim as new is:—

A container for garbage cans including angular corner posts, and side walls, the top and bottom of the container being open,

a cover for the open top of the container, a pair of cross bars secured between the pairs of angular corner posts at a point above the open bottom of the container and a shelf extending transversely across the upper edges of the bars for supporting the bottom of the garbage can adapted to be disposed within the container, the longitudinal side edges of the shelf being spaced from the adjacent sides of the container, the ends of the shelf engaging with the inner opposed faces of the opposite sides of the container.

In testimony whereof I affix my signature.

FRANK C. BRASTOW.
